LOCK

Abraham H. Golden and Charles Ledin, Stamford, Conn., assignors to The Yale & Towne Manufacturing Company, Stamford, Conn., a corporation of Connecticut

Application September 8, 1938, Serial No. 228,968

7 Claims. (Cl. 70—364)

This invention relates to a pin tumbler cylinder lock, and more particularly to means for preventing the unauthorized rotation of the key plug of such a lock.

5 Those skilled in the art fully appreciate that many means have been devised to prevent the picking of pin tumbler cylinder locks. Such means are usually of a character requiring a considerable number of parts, or extremely careful 10 manufacture, so as to increase considerably the cost of the cylinder locks in which they are embodied. Moreover, such means are usually of a character tending to complicate the operation of cylinder locks, so as to require considerable 15 servicing.

Our invention contributes to a pin tumbler cylinder lock a feature whereby, even though the tumblers of the lock be picked, it is impossible to rotate the key plug a sufficient distance to operate the lock.

20 More particularly, our invention is drawn somewhat along the lines of that disclosed in the patent to Pepper, No. 1,707,992, granted April 2, 1929. In the Pepper patent, there is formed in the cylinder an additional driver bore in which there is mounted a locking pin spring pressed toward the key plug. Should the key plug be rotated without the tumblers lined up with the plug periphery, as is the case when the tumblers are 25 picked, the locking pin is forced by its spring into one of the pin tumbler chambers as the key plug is rotated past the pin. To prevent the picking of the locking pin thereafter outwardly of the pin tumbler chamber into which it is pressed, Pepper 30 utilizes an additional deadlocking pin 19 which locks the locking pin in its locked position.

In our invention, we eliminate the additional deadlocking pin which is used by Pepper. We are able to accomplish this by having the locking pin 40 interlock with means which are preferably formed as part of the driver bore surface, as the locking pin moves into the pin tumbler chamber. This interlock prevents backward movement of the locking pin out of the pin tumbler chamber. 45 Preferably, this is accomplished by having the locking pin formed so that it cant under the influence of its spring, that is, moves angularly under the influence of its spring, as it is pressed into the pin tumbler chamber. As it cant, the locking pin moves into locking relation with a shoulder in the driver bore so as to prevent its being picked back out of the pin tumbler chamber.

In order to make it possible to service the cylinder, should the key plug be rotated and locked

by the locking pin, we back up the locking pin spring with a removable plug which is preferably screw threaded into the cylinder. By simply removing the threaded plug, it is possible to remove the locking pin and spring and replace the locking pin in its original position, thus rendering the lock fully operative once again.

We shall now describe a specific form of our invention shown in the accompanying drawing. Before doing so, we should like to point out that we consider this invention of relatively broad scope, and we do not wish to be limited in our monopoly except as is required by the state of the art, including the Pepper patent.

In the drawing, Fig. 1 is an elevation and partial section of a cylinder incorporating our invention. Figs. 2, 3 and 4 are sections taken along lines 2—2 of Fig. 1 illustrating the parts in various positions.

Referring now more particularly to the drawing, reference numeral 10 designates a standard type of cylinder lock having a key plug 11 in which are mounted a series of pin tumblers 12. The pin tumblers 12 cooperate with a series of drivers 13 arranged in driver bores 14 in the cylinder 10, the drivers being pressed downwardly into locking position by a series of springs 15, all as is well understood in the art.

In Figs. 2, 3 and 4, there is shown an additional driver bore 16 formed in cylinder 10, and in which is mounted a locking pin 17 having an angular upper surface 18 against which presses a spring 19 backed up by a removable threaded plug 20. There may be one or more of these bores and locking pins, and they may be positioned to cooperate with any of the tumbler chambers of the key plug. If a proper key, shown in section in Fig. 4 and designated by reference numeral 21, is inserted into the key way of the plug 11, all of the pin tumblers 12 will be 30 positioned with their upper ends aligned with the plug periphery, as is clearly shown in Fig. 4. If the key plug be now rotated, it will rotate in the usual way, and one of the pin tumblers 12 will prevent the locking pin 17 from being pressed by 35 its spring into the tumbler chamber in which the tumbler 12 is maintained.

Should the tumblers 12 be picked and the plug rotated without a key, and to the position of Fig. 3, it is obvious that the spring 19 will press the locking pin 17 downwardly and into the tumbler chamber of that tumbler pin 12 which is in alignment with the additional driver bore 16. Because of the formation of the extra driver bore 16, and because of the shape of the upper surface 18 of

the locking pin 17, pressure of the spring 19 will cause the locking pin to cant, or move angularly as in Fig. 3, at the same time that it moves into the chamber of the pin tumbler 12.

5. As is quite obvious, the extreme edge 22 of the pin 17 interlocks with the shouldered portion 23 of the driver bore 16, and with the parts in this position, it is impossible through pressure on the pin tumbler 12 to force the locking pin 17 back 5 into its bore, that is, into its position of Fig. 4. Because of this, it will be impossible to rotate the key plug 11 either in a clockwise or counter clockwise direction from the position of Fig. 3, and the lock will be inoperative.
10. 15. As we have already indicated generally, it is possible to remove the threaded plug 20, and thereby obtain access to the locking pin 17 and its spring 19. Locking pin 17 may then be released from its position of Fig. 3, and the entire 20 combination reset so that it may operate once again as in Figs. 2 and 4.

We now claim:

1. In a pin tumbler lock of the type having a key plug, and tumblers and drivers adapted to move in tumbler and driver bores and to be set 25 with their parting lines along the plug periphery, said lock having an additional driver bore spaced angularly from the usual bores and adapted for alignment with one of the tumbler chambers, a locking pin in said driver bore and a spring in said bore pressing said pin downwardly in the direction of said tumbler chamber whereby if the key plug is rotated without the tumbler in said chamber positioned with its upper end surface on the plug 30 periphery, said pin will be pressed into said tumbler chamber, said additional driver bore being formed to interlock with an integral part of said locking pin after said pin enters said tumbler chamber whereby to prevent retractive movement of said pin out of said tumbler chamber thereafter.

2. In a pin tumbler lock of the type having a key plug, and tumblers and drivers adapted to move in tumbler and driver bores and to be set 45 with their parting lines along the plug periphery, said lock having an additional driver bore spaced angularly from the usual bores and adapted for alignment with one of the tumbler chambers, a locking pin in said driver bore and a spring in said bore pressing said pin downwardly in the direction of said tumbler chamber whereby if said key plug is rotated without the tumbler in said chamber positioned with its upper end surface on the plug 50 periphery said pin will be pressed into said tumbler chamber, and a locking surface on said additional driver bore with which an integral part of said locking pin interlocks as it moves into said tumbler chamber whereby to prevent retractive movement of said pin out of said tumbler chamber thereafter.

3. In a pin tumbler lock of the type having a key plug, and tumblers and drivers adapted to move in tumbler and driver bores and to be set 65 with their parting lines along the plug periphery, said lock having an additional driver bore spaced angularly from the usual bores and adapted for alignment with one of the tumbler chambers, a locking pin in said driver bore and a spring in said bore pressing said pin downwardly in the direction 70 of said tumbler chamber whereby if said key plug is rotated without the tumbler in said chamber positioned with its upper end surface on the plug periphery said pin will be pressed into said tumbler chamber, an angular surface on said locking pin against which said spring presses whereby

to cant said locking pin in its bore as it is pressed into said tumbler chamber, and a surface of said bore with which said pin interlocks as it cant whereby to prevent retractive movement of said pin back out of said tumbler chamber.

4. In a pin tumbler lock of the type having a key plug, and tumblers and drivers adapted to move in tumbler and driver bores and to be set with their parting lines along the plug periphery, said lock having an additional driver bore spaced 10 angularly from the usual bores and adapted for alignment with one of the tumbler chambers, a locking pin in said driver bore and a spring in said bore pressing said pin downwardly in the direction of said tumbler chamber whereby if said key plug is rotated without the tumbler in said chamber positioned with its upper end surface on the plug periphery said pin will be pressed into said tumbler chamber, a surface on said locking pin 15 against which said spring presses designed so that said spring cant said locking pin as it is pressed into said tumbler chamber, and means with which said pin interlocks as it cant whereby to prevent retractive movement of said pin back out of said tumbler chamber.

5. In a pin tumbler lock of the type having a key plug, and tumblers and drivers adapted to move in tumbler and driver bores and to be set with their parting lines along the plug periphery, said lock having an additional driver bore spaced 20 angularly from the usual bores and adapted for alignment with one of the tumbler chambers, a locking pin in said driver bore and a spring in said bore pressing said pin downwardly in the direction of said tumbler chamber whereby if said key plug is rotated without the tumbler in said chamber positioned with its upper end surface on the plug periphery said pin will be pressed into said tumbler chamber, said locking pin being 25 smaller in diameter than at least a portion of its bore and formed so as to cant in said driver bore as it is moved under spring pressure into said tumbler chamber, and a surface of said bore with which an integral part of said pin interlocks as it cant whereby to prevent retractive movement of said pin back into said driver bore.

6. In a pin tumbler lock of the type having a key plug, and tumblers and drivers adapted to move in tumbler and driver bores and to be set 30 with their parting lines along the plug periphery, said lock having an additional driver bore spaced angularly from the usual bores and adapted for alignment with one of the tumbler chambers, a locking pin in said driver bore and a spring in said bore pressing said pin downwardly in the direction of said tumbler chamber whereby if said key plug is rotated without the tumbler in said chamber positioned with its upper end surface on the plug periphery said pin will be pressed into said tumbler chamber, said locking pin being formed 35 so as to cant in said driver bore as it is moved under spring pressure into said tumbler chamber, and means with which said pin interlocks as it cant whereby to prevent retractive movement of said pin back into said driver bore.

7. In a pin tumbler lock of the type having a key plug, and tumblers and drivers adapted to move in tumbler and driver bores and to be set 40 with their parting lines along the plug periphery, said lock having an additional driver bore spaced angularly from the usual bores and adapted for alignment with one of the tumbler chambers, a locking pin in said driver bore and a spring in said bore pressing said pin downwardly in the direction of said tumbler chamber whereby if said key plug is rotated without the tumbler in said chamber positioned with its upper end surface on the plug periphery said pin will be pressed into said tumbler chamber, an angular surface on said locking pin 45 against which said spring presses whereby to prevent retractive movement of said pin back into said driver bore.

- direction of said tumbler chamber whereby if said key plug is rotated without the tumbler in said chamber positioned with its upper end surface on the plug periphery said pin will be pressed into 5 said tumbler chamber, said locking pin lying partially in a portion of said additional driver bore which is substantially the same in diameter as said locking pin, and partially in a portion of said bore larger in diameter, said locking pin 10 moving into said larger diameter portion as it moves under spring pressure into the tumbler chamber, said locking pin having an angular surface against which its spring presses whereby it cant when in said larger diameter portion to interlock with a shoulder formed between the two 5 portions of said driver bore whereby to prevent retractive movement of said pin back out of said tumbler chamber.

CHARLES LEDIN.
